UNITED STATES PATENT OFFICE.

EUGENE J. MOYNIHAN, OF SAN FRANCISCO, CALIFORNIA.

STEAM-SHOVEL.

1,282,453.

Specification of Letters Patent. Patented Oct. 22, 1918.

Application filed February 3, 1917. Serial No. 146,363.

To all whom it may concern:

Be it known that I, EUGENE J. MOYNIHAN, a citizen of the United States, residing at San Francisco, in the county of San Francisco and State of California, have invented new and useful Improvements in Steam-Shovels, of which the following is a specification.

The primary object of the invention is, by adding a mechanism to the present forwardly digging shovel and without any change in the present construction of the machine, to convert the forwardly digging steam shovel into a back-action shovel, that is, one in which the material can be taken up on the backward stroke of the shovel. The result of this addition to the construction is that it provides in combination with the dipper and dipper handle of a steam shovel, means whereby a rock or stump, too large to enter the dipper and to be carried thereby, can be raised and delivered onto a car or on to higher ground. A further advantage of my invention is that my improved method does not require that the rock or stump should fall on to the bottom of the car so that there is no drop of the rock on to the bottom of the car, and moreover the rock can easily be dropped in the exact location desired within the car. Another advantage of the new construction is that it saves the expense of powder in breaking rocks and saves much time that would be otherwise lost on account of the necessity of using powder. Other advantages of my invention will appear from the description, and will be particularly pointed out in the claim.

In the accompanying drawing, Figure 1 is a side view of the operative portion of a steam shovel equipped with my invention; Fig. 2 is an end view of the same, the boom, dipper handle, and dipper being shown in dotted lines in other positions; Fig. 3 is a side view of the dipper and a portion of the dipper handle; Fig. 4 is a bottom plan view of the same; Fig. 5 is a side view of a ratchet hinge; Fig. 6 is a side view of a pawl and a counter-weight thereon; Fig. 7 is a similar view of another pawl without a counter-weight; Fig. 8 is a side view of a casting secured to a dipper handle and having a bearing for shaft; Fig. 9 is a broken side view of a shaft.

Referring to the drawing, 1 indicates a frame and 2 a front truck of a steam shovel to which my invention is shown as applied.

3 indicates a boom supported upon a casting 4, movable by means of a turn-table 6, said boom carries a dipper handle 7 pivoted upon a shipper shaft 8 having thereon 60 shipper shaft gear wheels 9. 11 indicates a dipper, pivoted at 12 on a casting 13 secured upon the end of the dipper handle, and said dipper handle is additionally supported by back braces 14. 16 indicates a 65 hoisting cable or chain secured to a sleeve 21, passing around pulleys 17, 18, 19, 20, and then around a hoisting drum 22 having an operating gear wheel 23. 24 indicates a door for closing the bottom of the dipper secured 70 to the ordinary curved hinges 25, hinged to the back of the dipper. All of the above is old and in common use and forms no part of my present invention.

To the door of said dipper are secured 75 curved racks having teeth 27 adapted to be engaged by pawls 28, 29, of which the pawl 28 has a rearward extension 31 carrying a counter-weight 30 said pawls being secured to a shaft 32 extending across the 80 bottom of the dipper handle and rotating in a bearing 33 carried on the under side thereof, and said pawls are formed with keyway 34 which fit loosely on a key in the shaft so that they can readily be removed 85 when not required. There is a hole 36 through the keyway of the shaft through which a pin can be driven after the pawl has been fitted to the shaft, said pin being preferably secured by cotters through its 90 ends. Said pawls have at their free ends hooks 35 which can engage the extreme ends of the racks and hold the door wide open. Pivoted to the under side of the dipper handle is a lever 38 which, by means of a 95 chain 39 actuates the door latch 41. To one end of said lever 38 is attached a chain 42, of which the other end is attached to the pawl 29.

The operation of my improved steam 100 shovel is illustrated in Fig. 2. Supposing that it is desired to load on to a car, shown at 40, a rock 43 which is too large to go through the dipper, then, as shown in full lines on the right of Fig. 2, in that case the 105 door 24 of the dipper is opened wide by the cable 44, the use of which is more particularly described in my U. S. Patent No. 1,210,194 of December 26, 1916, and when it has been thus fully opened it is held open 110 by means of said cable. The dipper is thus drawn rearwardly on to the rock until it

strikes against a large portion of the rock and the dipper cannot move farther rearwardly independently of the rock. When the rock has been moved into the dipper as far as possible, the cable 44 is slackened, and the door drops by gravity on to the large protruding portion of the rock and is locked in this position by the operator or crane-man slackening the line 46 attached to lever 38, thus permitting the pawls to drop into the ratchet teeth on the rear of the curved hinges 26 secured to the regular hinge. The rock is thus securely held in the dipper and may be lifted in the usual manner by hoisting line and transported, as shown on the left of Fig. 2, to a car and lowered thereinto. The dipper is lowered thereon until the rock rests on the bottom of the car, and the load is thus taken from the door of the dipper, and in that case the pawls can readily be released by suitably operating the boom engine, and pulling the line 46 to hold the pawls out of engagement.

From Fig. 1 it will be seen that at a higher level than that from which it is removed, or when the car is near the extreme load limit, with the ordinary construction of steam shovels it is impracticable to remove and deposit upon a railroad car a rock that is too

large to pass through the steam shovel dip-

per. A rock 53 is shown in the dipper, but there is no way of depositing the rock upon a railroad car, or at a sufficient distance, for there is no way in which the rock can be dumped out of the dipper at such height or 35 at such distance.

Further advantages of this construction are that, with the old construction, in which the rock enters the top of the dipper, it was impossible to determine whether the rock 40 was sufficiently small to pass through the dipper or not, because the dipper was between the observer and the rock, while with my present construction it is always easy to see how to move the dipper rearwardly so as 45 to work the rock into the dipper.

I claim:

In an excavator bucket having a door for closing the bottom of the bucket and hinged to its back, means to engage the door when 50 the door is swung wide open to hold the same open, means for pressing material into the bucket through the bottom while the door is open, means to hold the door from opening further due to the weight of the 55 material thus received in the bucket, and means, operable at will, for releasing said holding means.

EUGENE J. MOYNIHAN.
